(57) **CLAIM**

I claim the ornamental design for a support base for use with resistance bands, as shown and described.

DESCRIPTION

FIG. 1 is a top, front, right side perspective view of the support base for use with resistance bands, showing my new design;
 FIG. 2 is bottom, front, left side perspective view thereof;
 FIG. 3 is a top plan view thereof;
 FIG. 4 is a bottom plan view thereof;
 FIG. 5 is a front elevation view thereof;
 FIG. 6 is a rear elevation view thereof; and,
 FIG. 7 is a right side elevation view thereof, the left side elevation view being a mirror image thereof.

1 Claim, 6 Drawing Sheets**FIG. 1**

FIG. 2

FIG. 3

FIG. 4

FIG. 5

FIG. 6

FIG. 7
